FIG. 3

INVENTOR

Thomas W. Draper
BY Charles N. Butler

ATTORNEY.

UNITED STATES PATENT OFFICE.

THOMAS W. DRAPER, OF PHILADELPHIA, PENNSYLVANIA.

HAMMOCK.

No. 906,120.

Specification of Letters Patent.

Patented Dec. 8, 1908.

Application filed March 23, 1908. Serial No. 422,740.

To all whom it may concern:

Be it known that I, THOMAS W. DRAPER, a citizen of the United States, residing in the city of Philadelphia, county of Philadelphia, and State of Pennsylvania, have invented certain Improvements in Hammocks, of which the following is a specification.

This invention is designed to provide an improved hammock which the occupant can swing with a slight movement of the foot and which has convenient means for adjustment, to accommodate the occupant's size and inclination and for ready handling and shipping.

15 In the accompanying drawings, Figure 1 is a perspective view of a hammock embodying my invention; Fig. 2 is a perspective view of a second form; and Fig. 3 is a side elevation of a third form.

20 As illustrated in Fig. 1, the hammock has a main frame comprising the substantially horizontal side bars 1 connected together by the cross bars 2; the inclined side bars 3 connected together by the cross bar 4 and to the side bars 1 by the hinges 5; and the side bars 6 connected to the side bars 1 by the bolts 7 and to the side bars 3 by the bolts 8. An auxiliary frame, consisting of the side bars 9 connected at their outer ends by the cross bar 10, 25 has the inner ends of its side bars fulcrumed by the bolts 11 on the inner sides of the bars 1 so that it will swing within the inclined part of the main frame and be supportable at various elevations by a rod 12 which is 30 adapted for engagement in notches 13 of the inclined part of the main frame. A bail 14, having the pintles 15 which engage the outer ends of the bars 3, is connected by a rope or tension member 16 with a beam 17, to support 35 the head of the main frame. A bail 18, having the cross bar 19 adapted for receiving foot pressure and the pintles 20 adapted for engagement in the several notches 21 in the under side of the side bars at the foot of the 40 main frame, is connected by a rope or tension member 22 with a beam 23, to support the foot of the main frame. A bottom 24, 45 suitably of canvas, is secured to the horizontal part of the main frame and to the auxiliary frame. This arrangement permits the occupant of the hammock to recline at any angle desired, by reason of the adjustability of the auxiliary frame, and to swing the hammock by intermittent pressure with the toe 50 upon the cross bar' therefore, while the inclined members of the main frame serve as a

rest and guard for the side of the couch in addition to acting as a support.

As shown in Fig. 2, the structure can be modified by using a frame having the sections 25 and 26 connected by hinges 27 on the under sides thereof, and the section 28 connected to the section 26 by the hinges 29 on the tops thereof, the arrangement permitting the parts to be folded together within a small compass. To hold the section 28 at the desired angle with relation to the section 26, when the frame is supported by the engagement of bails (such as shown in Fig. 1) in the bearings 30 and 31, hinges 32 are fixed to the lower part of the section 26 and engage the corresponding part of the auxiliary section 28. The hinges have therein the holes 33 which engage the studs 34 carried by the section 28, permitting a ready change of the angle of the section 28 with reference to the section 26. I may also use side bars 35 having therein holes 36 for the engagement of bolts 37 which are fixed to the sections 26 and 28, whereby these sections may be held securely at any desired angle, the side bars acting as rests and guards as well as adjustable struts.

As shown in Fig. 3, there is employed a simplified construction comprising the sections 38 and 39 connected by hinges 40 on the top thereof, the section 39 having fixed thereto plates 41 which are adapted for engagement with the section 38 by removable pins 42, whereby the sections can be held in alignment for service or folded one upon the other for handling. A further or auxiliary section 43 is connected to the end of the section 39 by a hinge 44; the hinge having fixed to the section 43 a segmental plate 45 containing holes 46 which move over a plate 47 fixed to the section 39 and adapted to receive a pin 48 passed through one of the holes in the plate 45, whereby the section 43 can be held at any desired angle. Notches 49 and 50 in the respective sections 38 and 43 serve as bearings for bails such as 18 and 16 by which the structure is supported.

Having described my invention, I claim:

1. A hammock having a rigid frame and supporting mechanism comprising a device having an adjustable rocking connection by which the foot of said frame is supported, said device having a part disposed so that it can be pressed and rocked by the toe of an occupant to oscillate said hammock, an adjustable auxiliary frame connected to said

frame first named and supporting mechanism connected to said auxiliary frame.

2. A hammock having several bearings along its length and a supporting bail with 5 pintles adapted for making a rocking engagement with said bearings, said bail having a part whereby it is engaged and rocked by an occupant to oscillate said hammock longitudinally.
- 10 3. A hammock having a frame comprising side bars having bearing notches thereunder at different points along its length, in combination with supporting mechanism comprising a rocking device adapted for engagement in said bearings.

- 15 4. A hammock having a main frame, an auxiliary frame adjustable to different angles with reference to said main frame, means for holding said auxiliary frame against movement in either direction at various angles 20

with relation to said main frame, and supporting mechanisms respectively engaging said main and auxiliary frames whereby an occupant can swing said hammock.

5. A hammock having a main frame comprising side bars, a second set of side bars, perforated members hinged together and fixed to said side bars, and pins for fixing said hinged members together and holding said inclined bars in the desired relation, and 25 supporting bails having rocking connections with the respective frames.

In testimony whereof I have hereunto set my name this 21st day of March, A. D. 1908, in the presence of the subscribing witnesses. 30 35

THOMAS W. DRAPER.
